UNITED STATES PATENT OFFICE.

PARK EUGENE WELTON, OF AKRON, OHIO.

VULCANIZER.

1,121,214.

Specification of Letters Patent. Patented Dec. 15, 1914.

Application filed March 6, 1913. Serial No. 752,445.

To all whom it may concern:

Be it known that I, PARK EUGENE WELTON, a citizen of the United States, residing at Akron, in the county of Summit and State of Ohio, have invented new and useful Improvements in Vulcanizers, of which the following is a specification.

This invention relates to improvements in vulcanizers for holding nests of molds composed of separable portions firmly clamped together and inclosed by the vulcanizer body into which heat is admitted for curing the rubber articles contained in the molds.

The object is to provide a new and improved vulcanizer of the type referred to in which improved means are provided for removing the nest of molds from the vulcanizer, and having improved means for lifting the head or cover of the vulcanizer from the open body portion when required, the means for lifting the cover and for clamping the mold together within the vulcanizer being the same.

Other novel features will appear in the detailed description given hereafter and other special objects sought are described.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference-numerals indicate like parts in the different figures, Figure 1, is a view partly in side elevation and partly in vertical section on line X—X of Fig. 2; Fig. 2, is a plan view of a vulcanizer embodying this invention; Fig. 3, is a plan view of a ring employed for locking the cover in position; and, Fig. 4, end views of lugs on the locking-ring and vulcanizer for locking the locking-ring in position.

Referring to the drawings in detail, the reference numeral 1 denotes an upright casting or body portion preferably cylindrical in cross section and provided with a lower

end 2 mounted on a support 3 which in turn is mounted on a floor 4 and held in place through the medium of tie-bolts 5. The floor is preferably provided with an opening 6 through which extends a drain pipe 7 communicating with the interior of the vulcanizer body for their purpose of draining the water or condensed steam therefrom. The upper and normally open marginal portion of the vulcanizer is provided with a ring-shaped member or collar 8 which is provided with an upwardly-turned flange 9 which in turn is provided with a series of inwardly and horizontally-projecting lugs 10, regularly spaced apart, the spaces between these lugs 10 forming notches for a purpose to be later described. The closure device for this vulcanizer embodies a cover 11 provided across its under face with a plurality of ribs 12 for a purpose to be later described.

Secured to the cover 11 is a fixed ring 13, L-shaped in cross-section, and constituting a support for locking ring 14 which is revolute thereon. The locking ring is provided with a plurality of outwardly-extending lugs 15 corresponding to the lugs 10 on the flange 9 so that when the cover is lowered to position to bring the lower portion of the ring 13 at rest on the horizontal portion of the collar 8, the notches 15 on the revolute locking ring 14 will pass through the notches between the lugs 10, and when the locking ring 14 is given a partial rotation, the lugs 15 will interlock below the lugs 10, thereby securely holding the cover against upward movement.

In practice, I preferably incline the upper faces of the lugs 15 and under faces of the lugs 10 so that when they engage the wedging action will be set up by the revolution of the locking ring 14 to thereby securely seal the cover in position and render the joint between the cover and the vulcanizer fluid-tight. The cover 11 is provided with a pair of stuffing boxes or packing glands 16 through which extend vertically reciprocating rods 17, the packing glands rendering the joints between the cover 11 and the rods 17 fluid-tight during the movement of the latter. Slidably mounted on the rods 17 within the vulcanizer body 1 is a rack 18 preferably consisting of a plurality of radiating ribs. Secured to the inner face of the

body 1 is a flanged collar 19, which serves as a stop for the rack 18 at the lower end of its vertical reciprocation. The rack 18 is provided with openings which receive the vertical rods 17. Below the rack 18 the rods 17 are provided with stops or abutments 20 for a purpose to be later described. Above the vulcanizer cover 11 the rods 17 are also provided with stops 21. The cover is provided with a pair of upwardly-projecting hooks or eyes 22 for a purpose to be later described.

Secured preferably at opposite sides of the vulcanizer body 1 are a pair of rams 23 held in position through the medium of hold-fast devices 24 which preferably engage the body portion 1. The rams are each provided with interior bearings 25 in which are slidably mounted piston rods 26 being rendered fluid-tight through the medium of packing glands 27. The rams 23 are provided with inlets 29 and drain pipes 30. The upper ends of the piston rods 26 are shouldered and are provided with stops 31 for holding a cross-head 32 securely in position. This cross-head is preferably ring-shaped and is provided with inturned bifurcated lugs 33 between the members of each of which is pivotally mounted a hook 34 which is provided with a counterweight 35. The hooks 34 are preferably mounted above the loops or eyes 22 and are adapted to engage the latter when the cross-head 32 is lowered sufficiently. A heating fluid for causing the vulcanizing operation is introduced into the cylinder 1 through an inlet opening 36.

In practice, this vulcanizer will be usually mounted below the floor level of a factory, which floor level is indicated by the reference numeral 37 so as to enable the vulcanizer to be easily reached for filling and emptying.

In practice, the operation of the device is as follows: The operating fluid in the rams 23 is withdrawn allowing the cross-head 32 to fall low enough to enable the hooks 34 to engage the eyes 22, then the locking ring 14 is revolved sufficiently to disengage the lugs 15 from the lugs 10. Fluid under pressure is admitted to the rams 23 through the inlets 29 causing the pistons 28 to raise the cross-head 32 which lifts the vulcanizer cover upwardly and also lifts the rack 18 sufficiently high to permit the operators to place the molds on the rack 18 and in practice, this rack is usually lowered gradually as the molds are placed, the latter operation being permitted by slowly withdrawing the fluid from the rams 23. After the necessary amount of molds have been placed on the rack 18 the latter is lowered sufficiently to permit the cover to be placed temporarily in position, this latter operation being permitted by the fact that during the lowering of the cross-head sufficiently to lower the

cover to position the rods 17 will slide through the openings in the rack 18 until the hooks 34 can be disengaged from the eyes 22 after which the cover is seated. The locking ring 14 is then given a partial rotation to lock the cover in position. The pistons are then raised and in doing so, the abutments 19 on the lower ends of the rods 17 engage the rack 18 shifting the latter upwardly until the molds are clamped against the ribs 12 on the under face of the cover 11. After the molds have been firmly clamped together the heating fluid is admitted through the opening 36 until vulcanization has taken place.

I claim:

1. A vulcanizer comprising a body member and a cover therefor, a shiftable mold-carrying member operating to clamp molds against said cover, a vertically movable rod extending through said cover and connected with said carrying member, a cross-head outside of said vulcanizer to which said rod is connected, a ram outside of and positioned at one side of said vulcanizer for reciprocating said cross-head to thereby shift the position of said carrying-member.

2. A vulcanizer comprising a body member and a cover therefor, a shiftable mold-carrying member within said vulcanizer operating to clamp molds against said cover, a cross-head positioned outside of said vulcanizer provided with means for shifting the position of said cover, a rod connecting with said cross-head engaging said carrying member for shifting the latter, and a ram positioned outside and at one side of said vulcanizer for shifting said cross-head.

3. A vulcanizer comprising a body member and its cover, a pair of rams positioned outside of said body member and with their axes in parallelism with respect to the axis of the vulcanizer, a cross-head connected with the free ends of the pistons of said rams, means carried by said cross-head and cover arranged to interengage when the cross-head is moved to a lower position and thereby raise said cover when said cross-head is raised, rods extending from said cross-head through said cover into said vulcanizer, a mold-carrying rack within said vulcanizer engaged by said rods, a stop in said vulcanizer to limit the lower movement of said rack in unison with said rods and to permit the free sliding downwardly of the latter during the suspension of movement of said rack, and means on said rods to engage said rack and raise the same when said rods are raised by said cross-head to its upper position.

4. A vulcanizer comprising a body member and its cover, a mold-carrying member operating to clamp molds against said cover, a rod extending through said cover connected with said carrying member, a cross-

head outside of said vulcanizer to which said rod is connected, a ram outside of said vulcanizer for reciprocating said cross-head to shift the position of the carrying member, and suspending means depending from said cross-head, adapted to automatically engage said cover.

In testimony whereof I have hereunto set my hand in presence of two subscribing witnesses.

PARK EUGENE WELTON.
